DESIGN FOR A COMBINED EARRING AND PERFUME CONTAINER

Pasquale William Fanelli, Brooklyn, N. Y.

Application February 6, 1948, Serial No. 144,332

Term of patent 3½ years

(Cl. D45—9)

To all whom it may concern:

Be it known that I, P. William Fanelli, a citizen of the United States, residing at Brooklyn, in the county of Kings and State of New York, have invented a new, original, and ornamental Design for a Combined Earring and Perfume Container, of which the following is a specification, reference being had to the accompanying drawing, forming part thereof, in which—

Fig. 1 is a front elevational view of a combined earring and perfume container, showing my new design;

Fig. 2 is a bottom plan view; and

Fig. 3 is a rear elevational view.

I claim:

The ornamental design for a combined earring and perfume container, substantially as shown.

P. WILLIAM FANELLI.
